United States Patent Office

Des. 227,782
Patented July 17, 1973

227,782

TELEPHONE HANDSET

Norman Carroll Hazell, Freehold, N.J., John Niel McGarvey, Drexel Hill, Pa., and Robert Elwyn Prescott, Rumson, and Rembert Ryan Stokes, Middletown, N.J., assignors to Bell Telephone Laboratories, Incorporated, Murray Hill, N.J.

Filed Apr. 10, 1972, Ser. No. 242,908

Term of patent 14 years

Int. Cl. D14—03

U.S. Cl. D26—14

FIG. 1

FIG. 2

FIG. 3

FIG. 5

FIG. 4

FIG. 6

FIG. 7

FIG. 8

FIG. 9

FIG. 1 is a perspective view of our new design for a telephone handset;

FIG. 2 is a side elevation view of the telephone handset of FIG. 1, the opposite side being essentially a mirror image thereof;

FIG. 3 is a front elevation view of the telephone handset of FIG. 1;

FIG. 4 is an end view of the telephone handset along direction 4—4 of FIG. 3;

FIG. 5 is an end view of the telephone handset along direction 5—5 of FIG. 3;

FIG. 6 is a perspective view of a second embodiment of the telephone handset including an extendable band on one end thereof, all other features being substantially identical to the telephone handset of FIG. 1;

FIG. 7 is a perspective view of the end portion of the telephone handset of FIG. 6 showing the extendable band in a recessed position;

FIG. 8 is a side elevation view of the portion of the telephone handset of FIG. 7, the opposite side being essentially a mirror image thereof; and

FIG. 9 is a front elevation view of the portion of the handset of FIG. 7.

We claim:

The ornamental design for a telephone handset, substantially as shown and described.
